Inventor
A.E. CANTRELL

Ch. Parker Attorney

UNITED STATES PATENT OFFICE.

ADDIE E. CANTRELL, OF CAMP POINT, ILLINOIS.

DISPENSING DEVICE.

Application filed March 25, 1922. Serial No. 546,774.

To all whom it may concern:

Be it known that I, ADDIE E. CANTRELL, a citizen of the United States, residing at Camp Point, in the county of Adams and State of Illinois, have invented certain new and useful Improvements in Dispensing Devices, of which the following is a specification.

This invention relates to dispensing devices for oil cans, particularly adapted for use in filling oil reservoirs of motor vehicles.

An object of the invention is the provision of a spout which may be attached to an ordinary can having a valve therein, by means of which the discharge of liquid may be controlled.

A further object is to prevent the discharge of liquid until the spout has been inserted in the filling opening to prevent the contents of the can from dripping during tilting.

A further object of the invention is the provision of a plunger rod for operating the valve, and a tube forming the guide for the plunger rod and serving as a vent opening.

A further object is the provision of an auxiliary valve carried by the plunger rod to normally close the vent tube and prevent the liquid from backing up into the vent tube.

In the accompanying drawings, I have shown one embodiment of the invention.

35 In this showing:

Figure 1 is a perspective view of a can showing the spout attached and in operative position.

Figure 2 is a central vertical sectional view of a can showing the spout attached,

Figure 3 is a horizontal sectional view on line 3—3 of Figure 2, and,

Figure 4 is a detail view of the auxiliary valve.

45 Referring to the drawings, the reference numeral 1 designates a can of ordinary construction provided with a top 2 having threads formed thereon for the reception of a cover. The device forming the subject matter of the present invention consists of a cover 3, having an annular, threaded flange 4 adapted to engage the top of the can. A spout 5 is secured to the cover and registers with an opening therein. A valve 6 is hinged to the inside of the cover, as indicated at 7, and normally closes

the opening in the cover. The cover is provided with an opening 8 and a tube 9 is secured to the under side of the cover, in alignment with this opening. A plunger rod 10 extends through this opening and is provided with a knob or handle 11. The plunger rod is provided with an enlarged portion 13, below the tube, adapted to receive a leather or rubber facing 14, forming a valve to close the lower end of the tube. Beneath the tube, the plunger rod is provided with an offset base portion 15, and an arm 16, arranged substantially parallel to the body portion. The end of the plunger rod forms a hook 17, which is received in an eye 18 formed on the lower end of the valve operating rod 19. The valve operating rod is secured to the main valve, as indicated at 20. The end of the valve operating rod is continued beyond the eye 18, to form a hook 21 which is adapted to receive one end of a coil spring 22, the other end of the spring being secured to a stationary support, such as the exterior of tube 9, as indicated at 23. A second coil spring 24 is secured in the hook 21 and extends downwardly, this spring being attached to the arm 15, as indicated at 25. In Figure 1 of the drawings, I have illustrated a filling pipe 26 with the end of the spout arranged therein.

In the operation of the device, lubricating oil is ordinarily poured into the filling pipe 26 from any type of container through a funnel. When the container is tilted, some of the contents frequently run out before it is brought into alignment with the filling pipe and drip upon the body of the vehicle which is undesirable. By providing the valve 6, the container may be entirely inverted before any of the liquid will be discharged, and may be arranged in the position shown in Figure 1 of the drawings before the valve is opened. The valve is then opened, by depressing the rod 10, from the dotted line position in Figure 1 of the drawings, to the full line position. This places the spring 22 under tension and when the pressure is relieved on the end of the rod 10 the valve automatically closes.

The provision of a valve on the lower end of the plunger rod prevents the liquid in the container from flowing into the vent tube. When the vent tube fills with liquid, a partial vacuum is formed in the top of the container and when the main valve 6 is first

opened, the liquid does not run freely. If the vent tube is closed at its lower end, under normal conditions, a more ready flow of liquid is obtained when the valve 6 is opened. 5 The connection between the plunger rod and the valve rod 19 permits limited independent movement of these parts, and the spring 24 exerts an upward pull on the plunger rod to retain the valve 14 in closed position.

10 It is to be understood that the form of my invention herewith shown and described is to be taken as a preferred example of the same, and that various changes in the shape, size, and arrangement of parts may be resorted to without departing from the spirit of the invention or the scope of the subjoined claims.

15 Having thus described my invention, I claim:

- 20 1. An article of manufacture comprising a cover for liquid containers having an opening therein, a spout secured to said cover and embracing said opening, a valve hinged to said cover and adapted to close said opening, a vent tube depending from said cover, a 25 plunger rod extending through said tube, an auxiliary valve arranged on the lower end of said plunger rod and normally closing said vent tube, connections between said plunger rod and said hinged valve to open the valve when the plunger rod is depressed and means for normally retaining said valves in closed position.
- 30 2. An article of manufacture comprising a cover for liquid containers having an 35

opening therein, a spout secured to said cover in alinement with said opening, a hinged valve adapted to close said opening, a vent tube depending from said cover, a plunger rod extending through said tube, an 40 auxiliary valve carried by said plunger rod and adapted to close the lower end of the vent tube, a valve operating rod connecting said plunger rod and said hinged valve, and means for normally retaining said valves in 45 closed position.

3. An article of manufacture comprising a cover for liquid containers having an opening therein, a spout projecting from said cover in alinement with said opening, a 50 hinged valve secured to said cover and adapted to close said opening, a vent tube depending from said cover, an auxiliary valve adapted to close the lower end of said vent tube, a plunger rod extending through 55 said vent tube and operatively connected to said auxiliary valve, the lower end of said plunger rod projecting from said tube and provided with an offset portion, a valve operating rod connecting said hinged valve to the offset portion of said plunger rod, and a spring secured to said valve operating 60 rod and said vent tube to retain said hinged valve in closed position.

In testimony whereof I affix my signature 65 in presence of two witnesses.

ADDIE E. CANTRELL.
